UNITED STATES PATENT OFFICE

FRANS EDWARD FORSELL, OF CRANSTON, RHODE ISLAND, ASSIGNOR TO FREEMAN-DAUGHADAY COMPANY, A CORPORATION OF MASSACHUSETTS

CLASP

Application filed January 2, 1932. Serial No. 584,448.

This invention relates to a clasp for gripping the opposite surfaces at the edge of a fabric and may be used for holding a collar or the like in position or for holding a tie 5 in position on the shirt, and has for one of its objects to provide a construction which will securely grip the fabric at its edge without depending upon the resiliency of the clasp.

Another object of this invention is the provision of a pair of jaws pivotally connected together, the arrangement being such as to provide an eccentric mounting of one jaw with reference to the other so that movement about the pivot of one jaw moves it 15 toward or from the other jaw to grip the fabric placed between the jaws.

A further object of the invention is the provision of a straight jaw and a U shaped jaw pivotally connected so that one of the 20 arms of the U is housed between the opposite sides of the straight jaw with an enlargement at the end of the straight jaw approaching the free arm of the U shaped jaw when in such housed position to substantially meet the same 25 and lock a piece of fabric or the like between the jaws, the U jaw being relatively movable so that its free arm may become spaced from the enlargement to permit withdrawal or insertion of the fabric by reason of such movement.

A still further object of this invention is the provision of means to limit the relative movement of the jaws to either locked or released position.

With these and other objects in view, the invention consists of certain novel features of construction, as will be more fully described, and particularly pointed out in the appended claims.

40 In the accompanying drawing:

Fig. 1 is a view looking at the front or edge of the device with the jaws in closed or locked position.

Fig. 2 is a side elevation thereof.

45 Fig. 3 is a central sectional view showing the jaws in open position with fabric inserted therein to be moved to clamped position.

Fig. 4 is a view similar to Fig. 3 with the jaws moved to clamped position.

Fig. 5 is a side elevation of a modified struc-

ture showing a different form of stop for limiting the closing movement of one of the jaws and showing in dotted lines one of the jaws moved to open position.

Fig. 6 is a section on line 6—6 of Fig. 5. 63

Fig. 7 is a section on line 7—7 of Fig. 2.

Many collars or necktie holders now in use depend upon the resiliency of the stock for maintaining a gripping engagement on the opposite surfaces of the fabric with which they engage to hold the same in desired position, and to depart from this general arrangement and provide a clasp which will hold by its mechanical arrangement or swinging movement to permit insertion or release by 68 such movement I have provided a pair of jaws pivoted together, one of which is in the form of a U with one of its arms pivoted to the other jaw, the arrangement being such that upon swinging movement the arm of the U 70 jaw is moved toward or from an enlargement adjacent the pivot of the other jaw for a binding or releasing position of the jaws; and the following is a detailed description of the 75 present embodiment of this invention illustrating the preferred means by which these advantageous results may be accomplished.

With reference to the drawing, 10 designates one of the jaw members which is provided with opposite sides 11 and 12 connected by a bridge portion 13 at its middle point. Between the opposite sides 11 and 12, U shaped jaws 14 are provided, each having one of its arms 15 pivoted as at 16 between the sides 11 and 12 adjacent the end thereof. The jaws are of such length as to abut the connecting portion 13 to limit their movement to closed position in this direction, while these jaws may swing outwardly about the pivot 16 to provide a space 17 between the free arm 18 and the enlarged portion 19 of the end of the jaw member 10 for the insertion of the fabric 20 thereinto. A stop 21 extends across from the enlarged portion of one wall to the other wall to engage the cut-out portion 22 of this U shaped jaw and limit the opening movement thereof.

In attaching this clasp in position the U jaws are swung into position as illustrated in Fig. 3, either both together or preferably 100

one at a time, and the fabric 20 is inserted thereinto as illustrated in Fig. 3 after which the U jaw is swung to closed position as illustrated in Fig. 4 to bind the fabric between the arm 18 and the enlarged portion 19 to securely grip the same and hold the collar in position. After one side is applied the opposite side may be similarly applied. Thus it will be seen that the eccentric pivoting of 10 the U jaw causes the fabric to be more securely held as it is swung more closely toward the bridge portion 13 acting as a stop.

When in locked position as shown in Fig. 4 the necktie will cover the space 23 between 15 the bends of the U jaws, thus leaving exposed only the narrow edges of the U jaws as illustrated in Fig. 1, while, also the tie serves to prevent the outward swinging of the U jaws to permit release thereof.

20. In Fig. 5 I have illustrated a slightly modified structure in which the bar 24 is channel shaped throughout its length and stops 25 are provided by inserting a pin through the U jaw 14 for engagement with the edges of 25 the side walls 26 and 27 of the channel as illustrated in Fig. 6. This arrangement is released in a similar manner to that above described and illustrated in dotted lines in Fig. 5.

30. The foregoing description is directed solely towards the construction illustrated, but I desire it to be understood that I reserve the privilege of resorting to all the mechanical changes to which the device is susceptible, the 35 invention being defined and limited only by the terms of the appended claims.

I claim:

1. In a clasp for gripping a piece of fabric, a pair of jaw members, one jaw member 40 being pivoted with reference to the other jaw member to move bodily with reference thereto toward and away therefrom when swung about its pivot to grip or release a piece of fabric inserted between the jaw members, and a projection on one jaw member spaced from its gripping surface to engage the other jaw member and limit the movement of said jaw member in swinging about the pivot towards gripping position.

50. 2. A clasp for gripping a piece of fabric, a pair of jaw members, one jaw being channel shape in cross-section and the other being U shape with one of the arms of the U lying in the channel of the first said jaw and pivoted 55 adjacent the end of the channel, the other arm of the U jaw member lying out of the said channel and moving away from the channel member upon swinging of the jaw member about said pivot.

60. 3. In a collar holder, a bar, a pair of members each having spaced arms, one member having the end of one arm pivoted to one end 65 of said bar and swingable thereabout for the reception and clamping of a piece of fabric between said member and said bar, and the

other member similarly pivoted at the other end of the bar.

4. In a collar holder, a bar, a pair of U shape members oppositely disposed and pivoted to said bar adjacent its ends to swing 70 with reference thereto and receive pieces of fabric inserted between said bar and said members.

5. In a collar holder, a bar channel shape in cross-section, a pair of U shape members 75 oppositely disposed and pivoted to said bar adjacent its ends to swing with reference thereto and receive pieces of fabric inserted between said bar and said members, one of the arms of each U member lying between the 80 channel walls.

In testimony whereof I affix my signature.

FRANS EDWARD FORSELL.
